(57) **CLAIM**

We claim the ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion of the electronic device labeled 9 in FIG. 3; and,

FIG. 10 is an enlarged view of the encircled portion of the electronic device labeled 10 in FIG. 3.

The evenly-dashed broken lines in the figures depict portions of the electronic device that form no part of the claimed design.

The dot-dash broken lines in the figures illustrating portions of the electronic device that are shown in enlargements form no part of the claimed design.
